BAG SEAL AND HANDLE

Clifford J. Thompson, Davenport, Fla.

Application July 15, 1946, Serial No. 683,688

4 Claims. (Cl. 224—57)

1

This invention relates to devices for sealing a bag which is closed by a draw string and has for its principal object the provision of such a device which may be quickly and firmly applied and preferably has the additional advantage of serving as a handle for the bag.

At the present time fruit bags are generally of rather open mesh and are closed by a draw string which is pulled tight and then the string is wrapped around the mouth of the bag and knotted. After even a small amount of handling the knot becomes very firmly tied and it is difficult to untie the string.

The present invention contemplates a very simple and inexpensive strip of material having notches to receive the draw string and which will seal the bag very appreciably without the use of any knot at all.

In its preferred form, the sealing device may readily form a handle as it is quite elongated and has at the free end a point which ends rearwardly in a prong which can be readily caught in the mesh of the bag and is at a distance from the cord holding the recesses to afford a convenient grasp for the hand of the user.

In the drawings:

Figure 1 shows the preferred form of my device.

Figure 2 shows a modification.

Figure 3 is a further modification.

Figure 4 is an edge view.

In the preferred form, sheet material such as xylonite or any other plastic is used, but the device may be made of fibre, metal or other material. In the form which I have used, the holder is about $\frac{1}{8}$ " thick, $\frac{3}{4}$ " to 1" wide and 6" long, but I do not wish to be limited by these figures which are illustrative only.

One of the long edges of the strip, such as 10, has an indentation 11 leading through a wedge opening 12 into an eye 14. On the opposite long edge 15 there is a recess 16 leading to a bight 17 and in the nearby short edge of the device there is a bight 18. In use the two ends, 20 and 21, of the draw string of the net bag 24 are caught in the eye 14, preferably with the thumb of the user grasping the body 25 of the holder with the thumb adjacent the eye 14. The user may thus press the device firmly against the bag closing the mouth of the bag quite tight.

The string is then brought into the recess 16 and pulled into the bight 17, then crossed so that the string passes in the bight 18 and then brought in the recess 16 and pulled down either into the eye 14, or caught in the wedge slot 12, depending

2

entirely upon the relative size of the cord and the diameter of the eye 14. The cord thus forms an equilateral triangle as the cord holding recesses, that is, the eye 14 and the bights 17 and 18, are roughly equidistant. At the other end of the elongated body 25 the device is formed into a point 30 at the angle formed by the concave curve 31, and the convex curve 32. A recess 33 formed by the curves 34 and 35 form a hook 36 or prong which, after purchase of the bag of fruit, can be hooked into the mesh of the bag and especially if provided with an eye, such as 37, forms an anchor for the free end of the holder, whereby the holder forms a very convenient handle for the bag of fruit.

The pointed end 30 aids in pushing the free end of the holder through the mesh to space the threads of the net and this gives a much more permanent attachment than if the hook 36 were used alone, as it obviously may be.

In the form shown in Figure 2, the slots or bights 12, 17 and 18 are somewhat deepened so that the slots 40 and 41 may be identical but it is preferred that the short slot 43 in the short end 44 of the device be rather simple. The advantage of this form is that the cord may be caught in either the bight 40 or in the bight 41, whereas in the preferred form it is intended that the cord shall always be caught first in the slot 12.

30 In either form to seal the bag the operator needs only to slip the string in a holding notch, push the handle down the string to the mouth of the bag, pass the string over and down the notch on the opposite side of the holder and bring it up so it lies in the end notch or the notch of the shorter edge, then the string is returned down the first notch and the string is pulled tight. The string will not pull loose when tied in this manner and when the bag of fruit is sold the customer merely hooks the free end in the mesh of the bag and carries the bag away, the arrangement as shown in the drawings being such that the weight is perfectly balanced on the handle which may be and preferably is of transparent plastic and may or may not carry advertising or other printed matter.

In the modified form of Figure 3, the wedge opening and eye are modified by making the latter diamond shaped and the wedge slot is made 50 with almost parallel sides as shown at 50. The bight 51 is of more simple form than in the other figures while bight 53 in the short edge 54 follows the configuration of parts 43 and 44 of Figure 2. Whichever of the two strings 20 and 55 21 is passed through slot 50 last is wedged in the

V-shaped side of the notch and is held there by the other string. This notch will accommodate quite a range of sizes of string.

Having described my invention, what I claim is:

1. A handle for a bag of netted material and closed by a drawstring, comprising an elongated strip of flexible material having at one end a point formed by the junction of a concave curved edge and a convex curved edge, meeting in an acute angle, having a deep recess extending toward the point forming a hook adjacent the concave edge portion, having at the end farthest from the point a recess and on each of the two sides near said farthest end a cord receiving slot ending in an eye, whereby when the two cords of the draw string are inserted in one of the eyes and the strip is pressed down to the bag while holding the free ends of the draw string the bag is closed and may be held closed by winding the string through the other slot and the recess and back through the first eye and the strip may therefore become a handle by catching the hook in the net at a convenient point, the distance between the hook and the slots being at least as great as the width of an adult hand.

2. A device for holding the drawstring of a net bag to close the bag and serving as a handle for the bag when so closed, comprising an elongated

flexible strip at least four times as long as it is wide, having near one end a series of closely spaced cord holding recesses and at the opposite end a pointed hook to catch into the mesh of the bag material below the closure drawstring.

3. The device of claim 2 in which the series of recesses include a bight in one long edge, a wedge opening leading to an eye in the opposite long edge, and a third recess which is a bight.

4. The device of claim 2 in which the pointed hook has a deep indentation or recess beside the prong or back of the hook extending deeply into the strip at an angle very roughly 45° so that the point may be inserted into a mesh bag and the prong of the hook will prevent withdrawal of the strip from the bag.
